A. FIEN

METAL WINDOW

Filed Oct. 27, 1925

UNITED STATES PATENT OFFICE.

ALPHONSUS FIEN, OF NEW YORK, N. Y., ASSIGNEE TO S. H. POMEROY COMPANY, INC.,
OF NEW YORK, N. Y., A CORPORATION OF NEW YORK.

METAL WINDOW.

Application filed October 27, 1925. Serial No. 65,124.

To all whom it may concern:

Be it known that I, ALPHONSUS FIEN, a citizen of the United States, residing in the borough of the Bronx, of the city of New York, in the State of New York, have invented certain new and useful Improvements in Metal Windows, of which the following is a specification, reference being had to the accompanying drawing, forming a part hereof.

This invention relates to hollow metal window frames of the general construction indicated in applications for Letters Patent of the United States, Serial No. 24,747, filed April 21, 1925, and Serial No. 46,725, filed July 29, 1925. When windows of this general construction are installed on the job, it sometimes happens that by reason of slight variations in the width of the window openings in the masonry of the building, for example, the window sashes do not fit properly in the window frames, being sometimes capable of undue movement horizontally in the plane of the sash. It is the object of this invention to provide means whereby adjustment can be made readily to compensate for such variations in width and to secure the proper fit of the sash in the frame. The general construction illustrated in the applications above mentioned, in which the removable pulley stile is supported in the window jamb by internal braces of relatively heavy metal, lends itself to the application of the present improvement, in accordance with which each of such internal braces is slotted on two lines at one edge so as to form a tongue which can be bent slightly from the plane of the brace toward the sash so as to press the removable pulley stile more or less toward the sash and so take up the looseness which might otherwise be present, the pulley stile being held in place as usual by screws which hold it tightly against the support thus furnished by the tongues of the braces. The invention will be more fully explained hereinafter with reference to the accompanying drawing in which it is illustrated and in which:

Figure 1 is a view in front elevation, partly broken away and partly in vertical section, and also broken out to save space, of the upper, middle and lower portions of a window jamb to which the present improve-

ment is applied, the irregular plane of section being indicated by the broken line 1—1 of Figure 2.

Figure 2 is a view in sectional elevation, the irregular plane of section being indicated by the broken line 2—2 of Figure 1.

Figure 3 is a view in horizontal section on the plane indicated by the broken line 3—3 of Figure 1.

In the embodiment of the invention illustrated, the jamb is shown as having its main part *a* formed of sheet metal bent in the usual form and as having a removable, grooved pulley stile, made in two parts *b*, *b*¹, upper and lower, as described in said application, Serial No. 46,725 and as clearly shown in the accompanying drawing, the pulley stile engaging the main body *a* of the jamb as usual and as indicated in Figure 3. Vertical channels or grooves *a*¹, *a*², *a*³ and *a*⁴ are formed, as usual, in the face of the jamb and of the pulley stile for cooperation with the vertical edges of the upper and lower sashes *c* and *c*¹. In the application, Serial No. 24,747, the pulley stile is supposed to be in one piece from the head to the foot of the window frame, being supported at intervals by the internal braces above referred to, one such brace *d* being shown in the present drawing at the head of the window frame and another at the foot, such braces serving to stiffen the jamb as usual and to support the pulley stile as hereinafter explained. In the application, Serial No. 46,725, the pulley stile is also supported at the head and at the foot of the window frame by such an internal brace *d*, but the pulley stile is shown as made in two parts upper and lower, and the lower end of the upper part and the upper end of the lower part are shown as secured to and supported by what is called in said application a wedge block *e*, which is itself supported by a similar internal brace *d*.

In the present improved construction each of the internal braces *d*, except that one which supports the block *e*, is formed with a tongue *d*¹ at one edge, as by slotting on two vertical lines, as at *d*², which is capable of being bent from the plane of the brace toward the sash or window opening so as to form a support for the removable pulley stile, as shown in Figure 3, bearing, in the

construction shown, against the rear wall of the channels a^2 and a^3 . The tongue may also be formed with a trip d^3 to stand between the channels a^2 and a^3 and so align the 5 pulley stile. It will be evident that by bending the tongue more or less toward the sash or window opening, as the conditions of each case require, the pulley stile will be supported by the tongue in such position as to 10 compensate for variations in width and thereby take up such looseness of fit as may be objectionable. The pulley stile is secured to the braces d as usual, as by screws f , the pulley stile being held thereby firmly against 15 the tongues in their adjusted positions. In the case of the block e and the brace which supports it, the adjacent ends of the two parts of the pulley stile are secured to the block as usual by screws f^1 , the block itself 20 being secured by a screw f^2 to the corresponding brace d . At this point the desired compensation may be effected by placing shims, not necessary to be shown, between the block e and the brace d which supports it. 25

It will be noted that in Figure 1 of the drawing the thickness and size of the lower brace d are somewhat exaggerated, as com-

pared with the upper brace d , for the sake of great clearness in illustration. 30

I claim as my invention:

1. In a hollow metal window having a jamb with a removable pulley stile, a heavy brace within the jamb, said brace being formed with a tongue bendable to support 35 the pulley stile away from the plane of the brace.

2. In a hollow metal window having a jamb with a removable, grooved pulley stile, a heavy brace within the jamb formed with a tongue bendable from the plane of the jamb to support the pulley stile by contact with the rear wall of one of the grooves of the pulley stile. 40

3. In a hollow metal window having a jamb with a removable, grooved pulley stile, a heavy brace within the jamb and formed with a tongue bendable from the plane of the brace to support the pulley stile by contact with the rear walls of two of the grooves 50 of the pulley stile and with a tip to enter between the walls of such grooves to align the pulley stiles. 45

This specification signed this 22 day of Oct. A. D. 1925.

ALPHONSUS FIEN.
